ATTORNEY'S

UNITED STATES PATENT OFFICE.

JUSTIN McGRATH, OF SAN FRANCISCO, CALIFORNIA.

SHIP CONSTRUCTION.

1,314,069.

Specification of Letters Patent. Patented Aug. 26, 1919.

Application filed April 16, 1918. Serial No. 228,941.

To all whom it may concern:

Be it known that I, JUSTIN McGRATH, a citizen of the United States, and a resident of the city and county of San Francisco and 5 State of California, have invented certain new and useful Ship Construction, of which the following is a specification.

The invention relates to a combination steel and concrete ship, the bottom being of 10 steel and the sides of reinforced concrete.

An object of the invention is to provide 15 novel composite ship construction in which the steel portions of the hull are so arranged and constructed that an effective reliable and relatively strong reinforcing and anchoring 20 of the concrete portions of the ship with the metal portions is provided.

Another object of the invention is to reduce 25 the number of parts in constructing composite ships of the character described without detracting from durability and strength and to provide for rapid construction.

A further object of the invention is to provide 30 a novel effective and easily constructed means for securely joining or uniting the concrete sides of the ship at the bilge with the steel bottom.

The invention possesses other advantages 35 features, some of which, with the foregoing, will be set forth at length in the following description, where I shall outline in full, that form of the invention which I have selected for illustration in the drawings accompanying and forming part of the present specification. In said drawings I have shown one specific form of the hull of my invention, but it is to be understood that I do not limit myself to such form, since the 40 invention, as expressed in the claims, may be embodied in a plurality of forms.

Referring to said drawings:

Figure 1 is a side elevation of the hull of my invention.

Fig. 2 is a side elevation of a portion of 45 the hull before the concrete and the reinforcing is placed, showing the steel framing.

Fig. 3 is a half midship section of the hull of my invention.

In accordance with my invention I form 50 the hull of a steel frame, cover the bottom of the hull with steel plates which preferably extend upward for a short distance, on the side of the hull, and form the sides of the hull of reinforced concrete. The bow 55 and the stern of the hull are also preferably

constructed of steel plates. The skeleton of the hull is formed of steel shapes suitably spaced and arranged to withstand the strains to which the hull is subjected. The bottom 60 framing may consist of channels or angles 3, to the upwardly extending end portions 3' of which the ribs 4, which are preferably formed of channels, are secured. The bottom is covered with steel plates 5, riveted 65 to the framing, and these plates extend upward for a short distance on the sides of the hull, preferably to the top of the bilge. Secured to the ribs 4 at the inside of the hull at the bilge is an inner plate 6, which 70 forms with the outer bilge plates a pocket into which the concrete is subsequently poured. Those of the plates 5 which curve upwardly at the bilge are secured to the plates 6 by bolts 9 which lie within the 75 pocket and form an anchorage for the concrete which is poured therein and also stiffen the hull at the knuckle. Reinforcing material is arranged in the pocket and between the ribs, and the skeleton side of the 80 hull is inclosed in suitable forms and the concrete is poured. The knuckle pocket forms an anchorage for the concrete in the steel bottom and the ribs, which are riveted to the steel bottom, support and reinforce 85 the concrete sides.

At the bottom of the bilge, the reinforced concrete bottom 7 is raised above the steel bottom 5 and the hull is stiffened longitudinally by reinforced concrete beams 8 connecting the steel bottom with the concrete bottom. By providing a steel bottom for the hull, which is spaced from the reinforced concrete bottom and which is connected thereto at the sides by reinforced concrete beams, a full double bottom hull is provided, with the steel arranged to take up the strains due to grounding.

The decks 10 are preferably of reinforced concrete beams and slabs formed integral 100 with the ship's sides and are supported between the sides with reinforced concrete columns 12, which are placed along the longitudinal beams 8, thereby lending strength to the entire hull.

By this construction, a hull having a smooth steel bottom is provided, which offers less resistance to propulsion than a full concrete hull. By employing concrete sides and concrete beams, to withstand the 110 strains to which the hull is subjected, the amount of steel entering into the construc-

tion of the hull is greatly decreased and the employment of specially fabricated steel shapes is to a large extent eliminated. This construction lends itself to the rapid construction of hulls, possessing all of the advantages of steel hulls with the use of only a small proportion of the steel used in steel hulls and involves the use of only about one-third as many steel plates as are required in a steel hull.

I claim:

1. A ship having a steel frame, a bottom plating of steel, spaced inner and outer knuckle plates at sides of the bilge forming 15 pockets and reinforced concrete sides extending into said pockets.

2. A hull comprising a steel frame, steel plates covering the bottom of said frame, reinforced concrete covering the sides of said 20 frame and a reinforced concrete bottom spaced above said plates and integral with said sides.

3. A hull comprising a steel frame, steel plates covering the bottom of said frame, a 25 reinforced concrete bottom spaced above said steel plates and longitudinally disposed reinforced concrete beams connecting the bottom of said frame and said concrete bottom.

4. A hull having a steel bottom, a reinforced concrete bottom spaced above said steel bottom and longitudinal beams connecting said bottoms.

5. A hull comprising a steel frame, steel plates covering the bottom of said frame, 35 reinforced concrete walls covering the sides of said frame, a reinforced concrete deck formed integral with said walls, a reinforced concrete bottom spaced above said plates and integral with said walls, longitudinal reinforced concrete beams connecting the steel bottom with the concrete bottom and reinforced concrete deck supporting columns aligned with said beams.

6. A ship having a steel frame, a bottom 40 plating of steel, spaced inner and outer knuckle plates at sides of the bilge forming pockets, reinforced concrete sides extending into said pockets, and bolts extending through said pockets and connecting said 45 inner and outer plates.

In testimony whereof, I have hereunto set my hand at San Francisco, California, this 9th day of April, 1918.

JUSTIN McGRATH.

In presence of—

H. G. PROST.
